REMOVABLE HEEL FOR SHOES

Carlos Hall, Jr., Mexico, D. F., Mexico

Application August 21, 1933, Serial No. 686,148
In Mexico July 12, 1933

1 Claim. (Cl. 36—36)

This invention refers to a removable heel, and the object of the invention is to provide a heel which can be removed and replaced without the use of any special instrument or tool.

It is well known that the heel is the part of a shoe which is first worn and loses its shape, and if the worn heel is not repaired in due time, the whole form of the shoe may be affected. Many people do not have the heels of their shoes changed with the required frequency due to the bother connected with such a change when they have to send the shoes to a repair shop.

The present invention therefore solves this problem by enabling any person, without any special skill or previous knowledge, to change the heel of his or her shoes as many times as may be required. The invention is illustrated in the accompanying drawing in which:

Figure 1 is an exploded view in section of the device of the present invention.

Fig. 2 is a plan view of the rubber heel.

Fig. 3 is a bottom plan view of the attaching means.

Fig. 4 is a sectional view of the heel taken on line 4—4 of Fig. 2.

Fig. 5 is a sectional view taken on line 5—5 of Fig. 3.

Fig. 6 is a fragmentary side elevation of a shoe fitted with a heel according to the present invention.

In all the figures the same reference numbers refer to the same parts.

With reference to said figures, 1 is the shoe, 2 is the original base for the removable heel member, 3 is the upper plate of the removable heel. Said upper plate is provided with a number of projections 4 in the form of buttons and is fastened to the original base of the heel of the shoe in any convenient manner although in the drawing screws 5 are shown.

The rubber heel 6 is provided with a plurality of recesses 8 which, as shown in the drawing, are positioned near the upper surface of the rubber heel.

Openings 9 are formed in the material 10 between the recesses and the top surface of the rubber heel which provide access to the recesses so that the buttons 4 may be inserted into said

recesses. The diameter of the openings 9 are considerably less than the diameter of the recesses, so that once the buttons are inserted in the recesses they will not accidentally be removed. Preferably the diameter of the openings 9 is substantially equal to the diameter of the shanks of the buttons 4.

At this point it should be noted that the recesses are so near the upper surface of the heel that the material between the recesses and the said upper surface is of a thickness which is less than about one-half the depth of the recess. This relation between the thickness of the portions of material 10 and the depth of the recesses is important as the detachable feature of the rubber heel depends largely on this relation.

When the buttons 4 are forced into the recesses 8, the material 10 stretches to admit the buttons to the recesses and is pushed downwardly with a tendency to fill the recesses. If the above pointed out relation exists between the thickness of portion 10 and the depth of recesses 8, the buttons slip past the material 10 into the recesses. On the other hand, if the material 10 is greater than the depth of recesses 8 the material 10 is forced down to close the recesses and prevent the insertion of the buttons therein.

A rubber heel constructed as described above may be easily attached, removed and replaced on the heel portion of the shoe. Such a heel will not be accidentally displaced and will snugly fit on the shoe to provide effective and efficient service.

Having thus described my invention, what I claim is:

A detachable shoe heel comprising a rubber heel having a plurality of button-receiving recesses formed therein adjacent the top surface thereof, said top surface having openings therein of smaller diameter than the recesses to provide access to the recesses, the thickness of the material between the top surface of the rubber heel and the recesses being less than the depth of the recesses, and buttons carried by the heel portion of the shoe for entering the recesses for detachably connecting the heel to the shoe.

CARLOS HALL, JR.
